UNITED STATES PATENT OFFICE.

EDWARD S. PRESTON, OF CHICAGO, ILLINOIS.

DASHBOARD LAMP-SOCKET.

1,265,513.

Specification of Letters Patent.

Patented May 7, 1918.

Application filed May 23, 1917. Serial No. 170,419.

To all whom it may concern:

Be it known that I, EDWARD S. PRESTON, citizen of the United States, residing at Chicago, in the county of Cook and State 5 of Illinois, have invented certain new and useful Improvements in Dashboard Lamp-Sockets; and I do hereby declare the following to be a full, clear, and exact description of the invention, such as will enable 10 others skilled in the art to which it appertains to make and use the same.

My invention relates to sockets for electric lamps, and in its general aspects aims to provide a socket in which the lamp circuit 15 may be temporarily closed by the bodily movement of one of the socket parts with respect to the remainder of the socket. More particularly, it relates to a lamp lighting system and aims to provide a socket 20 which will enable the circuit to be closed independently by either of two switching means, one of which can be manipulated at the socket, and which may be embodied either with or without a grounding of the 25 circuit to metal parts of the socket. So also, my invention aims to provide a lamp socket in which the circuit to the lamp may be temporarily closed by moving a socket portion 30 associated with the lamp, as, for example, a hood or reflector partially housing the lamp.

In automobile practice, it has long been customary to mount a lamp on the dashboard in front of the chauffeur, so as to illuminate the speedometer, the safety lock, 35 etc., this lamp being commonly supplied with current from a storage battery. It has also been customary to use this lamp as an indicator for the effective operation of the oil pump, by connecting the lamp in a 40 circuit which will be automatically closed when oil is forcibly circulated, but which will be opened when the pump stops. While this check on the proper working of the oil pump has been satisfactory in many ways, 45 it involves a darkening of the dashboard when the engine and pump are shut down, thus making it difficult for the driver of the vehicle to find the keyhole of his safety lock after dark. To overcome objections of 50 this general order, my invention aims to provide a lamp socket suitable for a circuit controlled by the oil supply, but one in which the lamp circuit may also be temporarily closed by a simple manipulation of 55 the lamp bulb or some socket part associated therewith, as for example by pressure on the

reflecting hood commonly used over a dashboard lamp. In other words, I aim to provide a socket equipped with twin circuit portions, one of which portions is controlled 60 by a manipulation of a certain socket part.

In accomplishing the purposes of my invention, I may employ socalled double-pole lamps in connection with circuits entirely insulated from the metal parts of the socket; 65 or, I may ground one terminal of the circuit to certain metal socket parts and employ a socalled single-pole socket construction. Both of these embodiments are shown in the accompanying drawings and described 70 in the following specification, from which further objects of my invention will appear.

In the drawings, Figure 1 is a central longitudinal section through a double-pole socket embodying my invention. 75

Fig. 2 is an enlarged transverse section, taken along the line 2-2 and looking to the left in Fig. 1.

Fig. 3 is a similar section taken from line 3-3 and looking toward the right in Fig. 1. 80

Fig. 4 is a diagrammatic view of a pump and socket circuit employing the socket of Fig. 1.

Fig. 5 is a central longitudinal section through a single-pole or grounded shell 85 dashboard lamp socket embodying my invention.

Fig. 6 is a transverse section through the same, looking forward from the line 6-6 in Fig. 5. 90

Fig. 7 is a diagram showing the circuit connections as used with the socket of Fig. 7.

In the embodiment of Fig. 1, the socket of my invention includes an outer casing 1 or holder, here shown as secured to a dashboard 2, in which casing or holder an inner shell 3 is slidably mounted but limited in movement by suitable means, such as a screw 4 rigid with respect to the shell 3 and sliding in a longitudinal slot 5 in the casing 1. 100 The inner shell 3 is equipped at its forward end for interlocking with the base of a lamp 6 (as by bayonet slots 7 engaging pins 8 on the lamp base), which lamp has the ends of its filament connected to terminals 9 on the lamp base. Continuously engaging the respective terminals 9 of the lamp are conducting members 10 and 11 carried by an insulating body 12 mounted in the inner shell 3, each of which members desirably 110 consists of a cylinder carrying a spring-pressed plunger after the manner common

in sockets for automobile lamps. Both of the conducting members 10 and 11 extend to the rear end of the insulator 12 and one of the same (in this case the member 11) carries a plate 13 for extending its exposed rear surface as shown in Fig. 3.

Fast within the rear end of the outer casing 1 is an insulating plug 14 carrying terminals for three wires 15, 16 and 17, each of which terminals also consists desirably of a metal cylinder carrying a spring-pressed plunger extending forwardly beyond the plug 14 and toward the conducting members 10 and 11. Two of these terminals, viz. the ones associated with the wires 15 and 17 have plungers of such length as normally to contact respectively with the member 10 and the plate 13, while the plunger 18 on the terminal associated with the wire 16 is in alignment with another portion of the plate 13 but too short to contact with the latter when the inner shell 3 and the elements carried by the latter are in the position of Fig. 1.

25 In using the socket of Fig. 1 for the purpose mentioned, the wires 15 and 16 are connected to the terminals of a source of electricity, such as a battery 19, while the wire 17 leads to the terminal 20 of a switch 21 arranged for electrically connecting the wires 16 and 17 as shown in Fig. 4, this switch being closed by the upward pressure of oil 22 in a cylinder 23 on a piston 24 connected to the switch 21. Consequently, 30 when the oil is under pressure, the battery circuit to the lamp is closed through the wires 15 and 17. However, if the oil pump stops or ceases to create the pressure for which the piston 24 is adjusted, the switch 40 bar drops to the position shown in dotted lines, thereby extinguishing the lamp. Now, if the light of the lamp is needed before the pump is restarted (as for example, for finding the keyhole in a safety lock mounted on 45 the dashboard), the sliding shell 3 of the socket is pressed toward the rear against the resistance of the springs in the conducting members, until the plate 13 contacts with the short plunger 18. This closes the battery circuit through the wires 15 and 16, so 50 that the lamp will burn as long as the sliding shell 3 is pressed inward, but will go out again when the pressure is released. In other words, the bodily movement of the 55 slidably mounted portion of the socket serves to establish a shunt around the circuit portion comprising the switch 21, the wire 17 and the terminal associated with the latter. To prevent an overstraining of the 60 springs associated with the plungers, I desirably provide means for limiting the inward sliding of the shell 3, such as the shoulders 25 on this shell or a slot end arranged for engaging the screw 4. I also desirably provide a reflecting hood 26 par-

tially inclosing the lamp and mounted on the shell 3 so that the manual pressure may conveniently be exerted against this hood without touching and perhaps soiling the lamp.

70

However, while I have described my invention in connection with a socket having all parts of the circuit insulated from the metal socket parts and employing a so-called double-pole lamp, I do not wish to be limited to these or other details of the construction, purpose and arrangement above disclosed, it being obvious that the same might be modified in many ways without departing from the spirit of my invention. For example 80 Fig. 5 shows a socket having the wire 15 grounded to the outer casing and hence to the shell 27 on the lamp base which forms one terminal of the lamp, while the other lamp terminal 28 contacts with a single 85 plunger 29 carried by a conducting member 30 mounted in an insulator 31 which is fast in the inner shell. The conducting member 30 terminates at its rear in a plate 32 normally contacting only with the longer of two 90 spring-pressed plungers carried by the terminals of the wires 16 and 17, which terminals are mounted in an insulating plug 33 fast within the outer casing 1. In this case, the battery circuit is normally closed 95 through the switch and the wire 17, but may be closed through the switch-shunting wire 16 and the short plunger associated with the latter by bodily moving the lamp and the substantially T-shaped single intermediary conducting element toward the plungers, as shown in Fig. 7.

In either case, it will be obvious that my invention provides two paths for a portion of a circuit, which two paths can be independently controlled by separate switching means, and neither of which switching means interferes with the effectiveness of the other. By constructing the socket of two relatively movable parts, I am able to 110 provide the needed auxiliary switching means without the expense and inconvenience of a separate switch; and by utilizing the springs of the contact plungers for normally pressing the slidable socket portion 115 outwardly, I avoid the expense and space involved by using separate spring means for this purpose. Consequently, I am able to provide the additional feature of a manually operable switch for controlling the lamp 120 without materially adding either to the cost or the bulkiness of the socket.

I claim as my invention:

1. In a lamp-socket, a pair of relatively movable casing members one of which is interlocked with the lamp, a pair of circuit terminals carried by the other casing member and normally completing the circuit to the lamp, spring means for resisting a relative movement of the casing members in one 130

direction, and an auxiliary circuit terminal connected in shunt with one of the aforesaid terminals and arranged for closing its portion of the circuit only upon a relative movement of the casing members in the said direction.

2. In a lamp-socket for a circuit having a rupturable and an unrupturable portion in shunt with each other, a pair of relatively movable casing members one of which is interlocked with the lamp, spring means for normally resisting a movement of the casing members in one direction, and a pair of circuit terminals carried by the other of the casing members, one of the terminals being connected to the rupturable portion of the circuit and continuously electrically connected to a terminal of the lamp, and the other terminal being connected to the rupturable portion of the circuit and arranged for affording electrical connection with the same lamp terminal only upon a relative movement of the casing members in the said direction.

3. In an electric fitting, a pair of relatively movable members, a terminal-carrier interlocked with one of said members, a terminal plate associated with the terminal-carrier and connected to one of the terminals of the latter, and a pair of relatively insulated conducting elements carried by the other of said members, one of said elements continuously contacting with said plate and the other element disposed for contacting with said plate upon relative movement of the said members.

4. In a lamp-socket, a pair of relatively movable casing members one of which is interlocked with the lamp, and a pair of circuit terminals of unequal length both connected to the same end of the circuit, the longer of said terminals being arranged for continuously affording electrical connection to the lamp and the shorter one for affording such connection only upon relative move-

ment of the casing members, substantially as and for the purpose described.

5. In a lamp-socket as per claim 4, single spring means operating both for resisting a relative movement of the casing members, 50 and for maintaining the longer terminal continuously in electrical connection with the lamp.

6. In an electric fitting, a casing, a pair of wire terminals of unequal length housed 55 thereby and connected in shunt to a circuit, and yielding means associated with the casing for holding a lamp in a position in which it is continuously electrically connected to the longer of the said wire terminals 60 and in which it makes electrical connection with the shorter wire terminal only upon a bodily movement of the lamp with respect to the casing.

7. A lamp socket, including a holder, 65 means carried by the holder for holding the lamp and permitting a movement of the lamp with respect to the holder, a spring for resisting the said movement, a circuit terminal continuously connected to one terminal of the lamp, and an auxiliary member in shunt with said terminal and arranged for affording electrical connection to the same lamp terminal upon a movement of the lamp with respect to the holder against 75 the resistance of the spring.

8. In a lamp-socket, a casing, lamp-holding means arranged for permitting a movement of the lamp with respect to the casing, and a pair of circuit terminals both adapted 80 to afford an electrical connection for the same terminal of the lamp, one of said terminals being arranged for continuously affording the said connection and the other for affording the same only upon movement of the lamp with respect to the casing. 85

Signed at Chicago, Illinois, this 19th day of May, 1917.

EDWARD S. PRESTON.
